United States Patent Office

Des. 186,516
Patented Nov. 3, 1959

186,516

DESK OR THE LIKE

Robert I. Anderson, Muskegon, Mich., and David Chapman, Chicago, Ill., assignors to The Brunswick-Balke-Collender Company, Chicago, Ill., a corporation of Delaware

Application November 28, 1958, Serial No. 53,545

Term of patent 14 years

(Cl. D33—7)

FIG. 4

FIG. 5

Fig. 1 is a rear elevational view of the desk;

Fig. 2 is a side elevational view of the desk taken from the left of Fig. 1;

Fig. 3 is a side elevational view of the desk taken from the right of Fig. 1;

Fig. 4 is a front elevational view of the desk; and

Fig. 5 is a plan view of the desk.

The perforations fragmentarily depicted on the modesty panel in Figures 1 and 4 are continuous throughout.

We claim:

The ornamental design for a desk or the like, as shown and described.
